UNITED STATES PATENT OFFICE.

FRANK BURSIK, OF CHICAGO, ILLINOIS.

HOLDER AND FASTENER FOR STORM-SASHES AND THE LIKE.

No. 885,015.

Specification of Letters Patent.

Patented April 21, 1908.

Application filed April 24, 1907. Serial No. 369,974.

To all whom it may concern:

Be it known that I, FRANK BURSIK, a citizen of the United States, residing at Chicago, in the county of Cook and State of Illinois, 5 have invented certain new and useful Improvements in Holders and Fasteners for Storm-Sashes and the Like, of which the following is a specification.

This invention relates to improvements in 10 holders or fasteners for storm sashes and the like, and the primary object of the invention is to provide an improved device of this character which is adapted to fasten or lock the sash, and which is also adapted to hold 15 the sash open.

A further object is to provide an improved 20 device of this character adapted to be readily applied, and which will exert a spring tension upon the sash when closed to produce a tight connection.

A further object is to provide an improved 25 device of this character which will be simple, cheap and durable in construction, and effective and efficient in operation.

To the attainment of these ends, and the accomplishment of other new and useful objects, as will appear, the invention consists 30 in the features of novelty in the construction, combination, and arrangement of the several parts, hereinafter more fully described and claimed, and shown in the accompanying drawing illustrating an exemplification of this invention, and in which—

Figure 1 is a longitudinal sectional view of 35 a window casing and storm sash, with this improvement applied thereto. Fig. 2 is a detail perspective view of a portion of the storm sash and window casing, showing the sash in locked position. Fig. 3 is a perspective view of a holder or fastener constructed 40 in accordance with the principles of this invention. Fig. 4 is a detail sectional view illustrating a fastener in a position to hold the storm sash open. Fig. 5 is a detail view, 45 partly in section, of a supporting plate for the holder or fastener. Fig. 6 is a detail perspective view of a modified form of fastener.

Referring more particularly to the drawing 50 and in this exemplification of the invention, the numeral 10 designates generally a window casing provided with a blind stop 11, 12 and 13 designate storm sashes.

The construction of each sash being the 55 same, the specific description of one will apply equally as well to the other.

The sash is pivotally supported so as to swing outwardly from the window casing by means of a hanger or separable hinge designated generally by the reference numeral 21, 60 the specific construction and operation of which forms the subject-matter of a separate application. These hangers or hinges are preferably located adjacent the upper edges of the sash, and secured to the lower edge or 65 rail of the sash is a fastener or holder. This fastener or holder preferably comprises a body portion 22, one extremity of which is preferably bent back and forth upon itself, as at 23, to form a yielding or spring end, the 70 extremity 24 of which preferably projects beyond the end of the body portion 22 and is deflected laterally for a purpose to be set forth. This body portion 22 is preferably provided with a suitable aperture 25, by 75 means of which the holder and fastener may be secured in position.

Any suitable means may be provided for supporting the holder or fastener, but a simple and efficient means for accomplishing 80 this purpose comprises a plate 26 which is secured to the rail or sash in any desired or suitable manner, such as by means of screws or bolts passing through suitable apertures in the plate and into the sash. A headed 85 lug 27 is provided with a cylindrical body portion 28, and said cylindrical body portion is of a diameter to loosely fit within the aperture 25 in the body portion 22, and is of such a length that when inserted into the aperture 90 25 the head 27 will rest against one face of the body portion 22. This lug is secured to the plate 26 in any desired or suitable manner, preferably by means of one end 29 thereof being reduced and passed through a suitable aperture of the plate, the extremity thereof being off-set on the rear face of the plate. A suitable handle or arm 30 is connected to the body portion 22 in any desired or suitable manner, preferably by means of 100 the hinge 31, the pintle of which is preferably disposed transversely to the line of pivotal movement of the body portion 22 about the lug 27. This arm or member 30 may be of any desired or suitable length, and is provided with a headed knob or projection 32 extending beyond the upper edge of said arm or member, and which is located preferably adjacent the free extremity thereof.

Secured to the window casing, preferably 110 to the face of the blind stop 11 thereof, is a plate or member 33, which is provided with a

slot 34 extending longitudinally thereof, and disposed on an arc the chord of which is disposed toward the sash 12. This plate is also provided with an enlarged aperture or opening 35 adjacent one end of and communicating with the slot 34. The holder or fastener is secured to the window sash, preferably adjacent one of the lower corners thereof, and in such a position that the extremity 10 24 will project beyond the edge of the sash.

When it is desired to lock the sash, the latter is closed, so as to rest against the blind stop 11, the holder or fastener being previously moved about its point of pivotal support into the position shown in dotted lines in Fig. 2. After the sash is closed, the holder or fastener may then be moved from its dotted line position about its point of pivotal support, and into the position shown 20 in full lines in Fig. 2.

As the free extremity on which is located the knob or button 32 is lowered, the projection 24 of the body portion 22 will be raised, so as to enter the slot 34 in the plate 25 or member 33, the latter being located at a suitable point to permit the extremity 24 to enter the slot therein when the holder is moved to the position as shown in full lines in Fig. 2.

30 As the holder or fastener is moved into position, the extremity 24 will engage the walls of the slot 34; and the highest point of the arc formed by the slot is at a point to be engaged by the extremity 24. When the 35 holder or fastener is in a proper position to lock the sash, it will be noted that a tension will be exerted upon the spring or yielding end 23 of the body portion 22, thereby drawing the sash toward the blind stop 11 to form 40 a tight connection. If desired, a suitable stop 36 may be secured to the sash to form a support for the arm or member 30.

When it is desired to unlock the sash, all that is necessary is to raise or elevate the 45 free end of the arm or member 30, on which is located the knob or button 32, to the position shown in dotted lines in Fig. 2, which will cause the extremity 24 of the body portion 22 to pass out of the slot 34 in the plane 50 of the member 33. When the holder or fastener is in this position, or the position shown in dotted lines in Fig. 2, the sash may be moved outwardly so as to swing upon the hanger or hinge 21.

55 It will be noted that when the holder has assumed the position shown in dotted lines in Fig. 2, the knob or button 32 will stand adjacent the blind stop 11, and when the sash is swung about its hinge or support 21 60 to the position as shown in Fig. 4 of the drawing, the arm or member 30 may be moved about its point of pivotal support 31 with relation to the body 22 until the knob or button 32 is adjacent the enlarged 65 opening 35, and when in this position the

body 22 may be moved slightly further about its point of pivotal support, to cause the knob or button 32 to enter the enlarged opening 35, and by still further lowering the free extremity of the arm or member the 70 head of the knob or button 32 will pass behind the plate or member 33, while its shank will travel in the slot 34, as shown more clearly in Fig. 4 of the drawing; and when in this position the weight of the sash will 75 cause the shank to engage one of the walls of the slot 34, and hold the sash in its adjusted position; the body portion 22 and the end 23 being of such a length that when the holder or fastener is in the position shown in 80 Figs. 2 and 4 of the drawing, the extremity 24 thereof will not project beyond the lower edge of the sash.

The modified form of fastener shown in Fig. 6 of the drawing, is particularly adapted for use with ordinary sashes, and preferably comprises an integral member comprising the body 22, one end 23 of which is bent or deflected in the same manner as that shown in Fig. 3 to produce a yielding extremity 24, and the other extremity 37 is deflected laterally to form a projecting portion adapted to be used as a handle for moving the holder or fastener about its point of pivotal support. If desired, a suitable 95 handle 38 may be provided adjacent the deflected extremity 37.

In order that the invention might be fully understood by those skilled in the art, the details of the foregoing embodiment thereof 100 have been thus specifically described, but

What I claim as new and desire to secure by Letters Patent is:—

1. The combination of a window casing, a sash movably supported adjacent the casing, a locking member pivotally mounted intermediate its ends on the sash, one end of said member on one side of the pivot being bent back and forth upon itself to form a yielding extremity, and a handle operatively related to the other end of the member, said casing being provided with an apertured portion adapted to receive and exert a tension on the yielding extremity of the said locking member. 115

2. The combination of a window casing, a sash pivotally supported adjacent the casing, a locking member mounted on the sash for pivotal movement in a plane parallel with the face of the sash, said member being provided with a yielding extremity, and said casing being provided with an aperture adapted to receive the extremity and exert a tension thereon when the member is in an operative position and a handle pivoted to 120 said member, said handle being movable in the same plane with the body portion and adapted for independent movement in a plane transverse to the plane of movement of the said member. 125

3. The combination of a casing, a sash pivotally supported adjacent the casing, a member mounted on the sash for pivotal movement in a plane parallel with the face 5 of the sash, said member being provided with a projecting extremity, and said casing being provided with an apertured portion adapted to receive the said extremity of the member to lock the sash closed, and a handle pivoted to the member, said handle being adapted to be moved independently in a plane transverse to the plane of movement of the member, and means operatively related to the handle and adapted to enter the 10 said aperture when the handle is moved and when the said member is in an inoperative position for holding the sash away from the casing.
4. The combination of a casing, a sash 20 pivotally supported adjacent the casing, a member mounted on the sash for pivotal movement in a plane parallel with the face of the sash, said member being provided with a projecting extremity, a plate secured 25 to the casing, said plate being provided with a slot having an enlargement, said slot being adapted to receive the projecting extremity of the member to lock the sash closed, and a handle pivoted to the member and adapted
- to be independently moved in a plane transverse to the plane of movement of the said member, said handle being provided with a headed projection, and said projection being adapted to enter the said enlargement and pass behind the plate to hold the sash away 30 from the casing.
5. The combination of a window casing, a sash movably supported adjacent the casing, a locking member pivotally mounted intermediate its ends on the sash, one end of said member on one side of the pivot being bent back and forth upon itself to form a yielding extremity, a handle operatively related to the other end of the member, and a member secured to the casing, said member being 40 provided with a portion disposed on a curve and said curved portion being adapted to be engaged by the yielding extremity of the locking member to draw the sash against the casing.
- In testimony whereof I have signed my name to this specification, in the presence of two subscribing witnesses, on this 22nd day of April A. D. 1907.
